REVERSIBLE FAN
 Lowell T. Caston, Robert Lee, Tex.
 Filed May 7, 1963, Ser. No. 278,705
 1 Claim. (Cl. 170—160.43)

This invention relates to a reversible fan, and more particularly to an industrial type of fan wherein the pitch of the fan blades may be reversed while the fan continues to rotate.

A further object of this invention is to provide an industrial type reversible fan which is very simple in construction and in operation, which may be readily taken apart for servicing and readily assembled or reassembled with ordinary tools.

Still a further object of this invention is to provide a reversible fan wherein the pitch of the fan blades may be changed between a forward and a reverse position, as well as a neutral or feathering position.

Still a further object of this invention is to provide an industrial type of reversible fan for use wherever desired, and particularly, for use in connection with an industrial engine such as on a drilling rig, or more particularly, on a crawler type of tractor, wherein the operator may adjust the pitch of the blade as desired, while the motor is operating thus placing the pitch of the blade at a neutral or feathering position when the engine is first started, enabling the engine to warm up more quickly, then shifting the blade to a position to suck air through the engine radiator and to keep the engine at proper temperature. However, when desired, the pitch of the blade may be readily reversed while the engine continues to operate, so as to blow against the radiator, if necessary as, for instance, when the radiator may have accumulated some brush, trash or dirt thereon interfering with cooling, as may well happen when it is used in areas having a lot of brush or trash.

Still a further object of this invention is to provide a rotary fan having a reversible pitch controlled by a rack and gear connection to each fan blade shaft, wherein the rack may be readily moved to different positions while the fan blade is rotated, to controllably change the pitch of the fan blade between forward, neutral and reverse positions.

With the above and related objects in view, this invention consists in the details of construction and combination of parts as will be more fully understood from the following description, when read in conjunction with the accompanying drawings, in which:

FIG. 1 is a perspective view of the fan of this invention.

FIG. 2 is a sectional view on line 2—2 of FIG. 1, extending longitudinally of the fan blade mounting.

FIG. 3 is a transverse sectional view on line 3—3 of FIG. 2.

FIG. 4 is a sectional view through the rack and gear control means on line 4—4 of FIG. 2.

There is shown at 10 the fan of this invention, consisting of one or more fan blades 12 secured on a fan blade shaft 14, the fan blade shaft 14 extending into the blade rotating unit 16. The fan blade rotating unit 16 consists of an outer sleeve 18, a concentric inner sleeve 20 spaced within the outer sleeve 18, and a cylindrical rack sleeve 22 axially slidable between the outer sleeve 18 and the inner sleeve 20.

The outer sleeve 18 and the inner sleeve 20 are secured for operation as unit 16 by the fan blade shafts 14 extending through aligned journal openings 32 and 34 in the outer and inner sleeves 18 and 20, and held there-to by nuts 36 threaded on the inner ends thereof.

2

The axle or sleeve 22 extending between the inner and outer sleeves is provided with an axially extending slot 38 for each fan blade 14 so that the sleeve 22 may be extended sufficiently beyond the fan blade shaft 14, and one axially extending wall of each slot 38 has rack teeth 40 formed therein and meshing with the teeth of a gear 42 which is fixed on the fan blades 14. One slot 38 with its rack 40 is provided for each fan blade shaft 14, six such blades and fan blade shafts being shown herein.

As will be apparent from FIG. 2, axial sliding movement of the rack sleeve 22 in one direction or the other will correspondingly rotate the fan blade shafts 14, and thus the fan blades 12. The ratio of the gear 42 to the rack 40 is such that the blades 12 may be set between a forward pitch for normal operation in the case of the radiator, for sucking air through the radiator, a neutral pitch (or a feather pitch) wherein no air is moved, as when speeding up the heating of the engine, and a reverse pitch wherein air is blown against the radiator so as to clean out any dust, trash or debris that may accumulate thereon.

To hold the blades at any one of these three positions, four cooperating detents 44 with springs 46 urging them outwardly of recesses in the rack 22 is provided, and four sets of each three detent-receiving recesses 48, 50 and 52 are provided in one of the sleeves, here shown as the outer sleeve 18. When the detents are in the recesses 50, the blade 12 is in the neutral or feathering position, as illustrated. Pushing the rack 40 axially in a right hand direction as illustrated in FIGS. 1 and 2, will cause the blade to rotate in a position to cause air to move in a left direction, while moving the rack 40 so as to bring the detents 44 into the recesses 52 will make the air move in the opposite direction.

In order to slide the rack 40 one way or the other, and still permit it to rotate as a part of the unit 16, with the outer sleeve 18 and inner sleeve 20, a thrust bearing 54 is secured on one end of the rack sleeve 22. The outer race 56 of thrust bearing 54 is provided with a pair of diametrically opposed bosses 58 cooperating with the slots 60 of a fork 62 having a control lever 64 pivoted by a stud bolt 66 to a support arm 68, so that movement of the control lever 64 through the slot 60 and boss 58 will axially move the thrust bearing 54, and thus the rack sleeve 22 secured thereto, to thus control the rotation of the fan blade shaft 14 and the positioning of the blades 12.

The fan blade unit 16 is powered for rotation in any conventional manner. As here shown, a pulley 70 is mounted on the outer side of the sleeve 18 of the unit 16 for operation by a pulley belt from the engine (not shown) in a conventional manner. The fan blade unit 16 is mounted for ready rotation by having a pair of bearings 72 mounted therewith on a bearing shaft 74 in a conventional manner. A nut 76 is provided at the outer end of the bearing shaft 74.

In operation, the manner of assembling or disassembling the parts of the fan 10 of this invention is obvious from the foregoing description. With the engine running, and thus the fan unit 16 in rotation, the fan blades 12 may be set at one of the three desired positions by manipulating the lever 64 so as to advance or retract the rack sleeve or cylinder 22. When the spring pressed detents 44 have been brought to the position of being in the detent recesses 50, the fan blades 12 are in a neutral or feathering position, and will not move air in either directions. Advancing the sleeve rack 22 by manipulating the lever 64 to bring the ball detents 44 to the recesses 52 will cause the air to move in one direction, while retracting the rack sleeve 22 to bring the ball detents 44 into the recesses 48 will cause to reverse its pitch to move the air in the opposite direction.

3
The normal direction of operation will be to suck air through the engine radiator, but when the engine is part of a crawler tractor, for instance, and operating where there is a lot of dirt, brush or debris present, some of the dirt, dust or debris will tend to accumulate on the radiator and clog the pores thereof, thus causing the motor to overheat. Instead of permitting such dust or dirt to accumulate, the operator may manipulate the lever 64 every once in a while to reverse the pitch of the fan blades 12 to cause the air to travel in the opposite direction and blow away the accumulated dirt, dust or debris before it has accumulated a sufficient amount to cause overheating of the engine, and then the blade pitch is again reversed, to cause it to cool the radiator in the normal manner. This operation can continue without stopping the engine, or even stopping the operation of the unit on which the engine is mounted. The operator momentarily manipulates the lever 64 so as to keep the radiator continuously clean.

In addition to being used on vehicles such as a crawler type tractor, it can be also used on drilling rigs or other stationary engines thus enabling such engines to be located where desired and have the air from the fan blades be directed in the desired direction at any time.

Although this invention has been described in considerable detail, such description is intended as being illustrative rather than limiting, since the inventions may be variously embodied, and the scope of the invention is to be determined as claimed.

Having thus set forth and disclosed the nature of this invention, what is claimed is:

A reversible fan comprising a pair of concentric separable spaced apart cylindrical sleeves, a fan blade shaft journaled radially through said two concentric sleeves and holding said cylindrical sleeves against movement relative to each other, a gear fixed on said fan blade shaft in the space between said two concentric sleeves, a cylin-

4
drical sleeve axially slidable between said two spaced apart concentric sleeves, said axially slidable sleeve having an axially extending slot therein and rack teeth integrally formed on one axially extending wall of said slot in mesh with said gear fixed on said fan blade shaft, and means for axially sliding and holding said cylindrical sleeve to rotate said fan blade shaft and means to hold it in set positions while said three sleeves are rotating as a unit, said sliding means comprising thrust bearing means mounted on said cylindrical rack sleeve, a forked lever cooperating with said thrust bearing to axially slide said cylindrical rack sleeve between said two spaced apart concentric sleeves, said holding means comprising spring pressed detent means, and spaced apart detent cooperating recesses cooperatively mounted in said cylindrical rack sleeve and one of said concentric sleeves, a bearing shaft extending through said inner concentric sleeve, and spaced bearing means adjacent opposite ends of and within said inner sleeve rotatably supporting said sleeves as a unit on said bearing shaft, and power receiving means comprising a pulley fixedly mounted on and about said outer concentric sleeve.
